UNITED STATES PATENT OFFICE.

CHARLES R. WITTEMANN, OF NEW YORK, N. Y.

STABILIZING-VANE.

1,160,354.

Specification of Letters Patent.

Patented Nov. 16, 1915.

Application filed March 12, 1915. Serial No. 13,831.

To all whom it may concern:

Be it known that I, CHARLES R. WITTEMANN, a citizen of the United States, and resident of the borough of Richmond, in the county of Richmond and State of New York, have invented certain new and useful Improvements in Stabilizing-Vanes, of which the following is a specification.

This invention relates to vertical stabilizing vanes for flying machines, and my improvements consist in a certain vane formation including curves and angles which coördinate to correct over-balancing pressure tendencies. In brief, my improved vanes, which are intended to be mounted, either rigidly for automatic service, or pivotally for manual control at opposite ends of a supporting plane, are so shaped and arranged, that the forward portion of each 10 vane is presented edgewise in the direction of flight, while the upper and lower rearward portions thereof are outwardly and oppositely curved, whereby in effect the upper and lower corner portions possess curvilinear contours with approximately bisecting medial lines. In this manner, the pressures being constant, and the curved over-hang at its upper rear portion offering a positive, pressure supporting angle to the 15 air currents or columns, the vane will be normally in vertical position with the air craft traveling on an even keel, but when that pressure becomes abnormal sufficiently to create a tendency to establish a high side 20 to the machine, then the curved over-hang of the vane at the abnormal pressure receiving side, in the act of elevating in a turning movement which concurrently depresses the opposite side of the machine, thereby 25 changes to a negative angle with a consequent diminution of pressure support. At the same time the other vane of the pair, correspondingly, though oppositely arranged and mounted at the other end of the 30 supporting plane, increases the positive angle of its rearward upper curved portion, to thereby exercise greater lifting effort at the low side of the machine, whereby the excess of positive angle on the low side, conjoined 35 with the negative angularity at the high side, serves to neutralize the effect of the over-balancing tendency.

The curvature at the lower rear portion of the vane has the effect, with respect to the vane at the high side of the machine, of more rapidly bringing the lower portion of

said vane to a negative angle, while, on the low side of the machine, the corresponding curvature of the opposite vane of the pair, affords, with the curvature at the rearward upper portion, a non-spilling pressure receiving surface which is highly efficient. Said lower rear curvature also exercises the extremely important and novel function with a vane at the high side of enabling abnormal pressures encountered in the line of flight to provide a depressing force at said high side, which force becomes more pronounced proportionately as the upper curvature recedes from its positive degree of pressure containing angularity toward the negative angle, acting further with the restraining influence of a brake to prevent oscillatory action and thus steady the machine under pressure variations. Thus it will be seen 40 that with a pair of the aforesaid vertical vanes secured at opposite sides of an aeroplane, for lateral balance, the vane which is at the side of the machine subjected to the greater air pressure, causing it to tilt upwardly and become the high side, will, thereby, at its upper curvature, assume a negative angle and thus spill the pressure, while its lower curvature will at the same time become more positive, whereby that same 45 greater pressure, in increasing ratio with the upward tilting of the machine at that side, bears upon said lower curvature with depressing influence relatively to the high side of the machine. At the same time the vane 50 at the side of the machine receiving less pressure, thereby becoming the low side, acquires considerable increase in the pressure supporting capacity of its upper curvature, which assumes a more positive angle; 55 and, also, the lower curvature of that vane, while taking a negative angle with relation to the encountered pressure, provides, with the upper curvature, a powerful brake to prevent side slippage of the machine, in this 60 respect proving equally efficacious while banking in making a turn as in performing the function of stabilizing.

The general contour of each vane, irrespective of the upper and lower curvatures 65 referred to, is that of a parallelogram, excepting that at its lower forward portion its terminal edge extends rearwardly from a point of the front edge to the base, thereby restricting the extent of the lower forward 70 portion of said vane, for the purpose of enabling encountered pressures to more read-

ily co-act with the rearward upper and lower curved portions of the vane as stated.

In the instance of the vanes aforesaid being mounted for manual control, they may 5 be pivoted about parallel axes, and provided with means to hold them in a set position, together with means for varying them from that position at the will of the operator in any known manner.

10 Other features and advantages will hereinafter appear.

In the drawings; Figure 1 is a side elevation of a portion of an aquairplane showing mounted thereon one of my improved 15 vanes. Fig. 2 is a perspective side elevation 20 of a vane, as pivotally supported for manual control. Fig. 3 is a rear end perspective view of the vane. Fig. 4 is a horizontal section through the upper portion of Fig. 2, and Fig. 5 is a reduced plan view, immediately broken away, showing a pair of vanes arranged one at each end of the supporting 25 surface.

My improved vertical balancing vanes are 25 intended to be arranged transversely relatively to the supporting planes, or longitudinally in the direction of flight. In Fig. 1 a 30 vane, as 1, is shown as rigidly mounted at one end of a bi-plane supporting unit, said vane having the upper, rearward and outward curvature 2, and the lower, rearward and outward curvature 3. To comprise an 35 operative pair of such vanes a similar one would be correspondingly mounted at the opposite end of said bi-plane unit. Or said 40 pair of vanes might be disposed in any other desirable positions within the lateral extent of the supporting planes, whether the plane units be of the bi-plane, monoplane, 45 or multi-plane type. Being rigidly mounted, the vanes, of which there may be one or more pairs, are movable only with and in the movement of the entire machine, and it is due to the structural formation of said 50 vanes that they are able to compensate for the variations of pressure met with to afford inherent stabilization.

The forward portion of the vane, as at 4, is flat, and directed forwardly in the line of 50 flight, though having a slight outward divergence. Rearwardly from the flat portion, as at 2, the material of the vane assumes approximately the contour of a conic section, whereby the upper rear corner of 55 the vane, instead of being rectangular, has an outward curve which presents a lifting surface whose resistance to the supporting 60 pressures varies according to the angle which said pressures give to the machine. Also at the lower rear portion of the vane its material follows a roll or curvature 3 whose medial line intersects the medial line of curvature 2, said curvature 3 affording a

downward pressure surface which enables pressures encountered in the line of flight to 65 exercise a depressing influence upon the vane, thereby counteracting excessive lift and serving to prevent oscillatory action of the machine under varying pressures.

The correctional value of the curvatures 70 in the vane at the high side is augmented by the corresponding curvatures of the vane at the low side, where the upper curved portion 2 provides a more positive supporting surface as inclined with the tilt of the machine, and where the lower curved portion 3 co-operates with said upper curved portion in the provision of a drift or slip retarding device; the conjoint action of the said vane characteristics thus effectively restoring 80 equilibrium of the machine as and when disturbed. The under forward portion of each vane is bounded by an inclined edge extending downwardly from the vertical front edge to the horizontal bottom edge of the 85 vane, whereby is facilitated the introduction of air pressures to the surfaces of the upper and lower rearward curved surface portions aforesaid.

As shown in Fig. 2, the vanes 1 may be 90 pivotally supported, as at 5, to be in this manner capable of manipulation where it is desired to have the stabilizing vanes under manual control.

Variations may be resorted to within the 95 scope and spirit of my invention, and parts thereof used without others.

I claim:—

1. A vertical balancing vane for aeroplanes arranged with its forward portion 100 straight in the line of flight, and its upper and lower rear portions outwardly curved from a common center, to afford pressure receiving surfaces, which respectively function to increase their positive and negative 105 angles to stabilize the aeroplane against the variable pressure disturbing influence to which it is subjected, and which jointly serve to steady the aeroplane against oscillatory motion.

2. The combination, with an aeroplane, of 11 a pair of vertical vanes arranged respectively at opposite sides of its longitudinal axis, said vanes lying in the direction of flight, and being each outwardly curved 11 respectively at their rear upper and lower portions over intersecting radial lines, to provide stabilizing surfaces.

Signed at the borough of Manhattan in the city, county and State of New York this 12 day of March A. D. 1915.

CHARLES R. WITTEMANN.
